FEELER MECHANISM FOR LOOMS.

1,387,322.

Specification of Letters Patent. Patented Aug. 9, 1921.

Application filed March 1, 1920. Serial No. 362,379.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

10 The present invention relates to feeler mechanisms for looms whereby the filling in the shuttle may be replenished prior to complete exhaustion thereof.

15 In that type of feeler mechanism wherein the feeler is moved longitudinally of the shuttle when the filling is substantially exhausted on a detecting beat, it has been common heretofore to effect such "side swipe" or lateral movement of the feeler member either by means of the forward pressure thereagainst, on a detecting beat, or by means of mechanical devices which act upon the feeler. The present invention relates 20 more particularly to feeler mechanisms of the first-mentioned type, that is, where the forward pressure upon the feeler member effects side swipe or lateral movement of such member when the filling is substantially exhausted.

25 The feeler mechanism must be sensitive either to the presence or substantial absence of filling in the shuttle, and must be responsive to either condition, either to prevent or 30 to cause filling replenishment. Should the feeler mechanism call a change prior to the time when the filling in the shuttle has reached a substantial degree of exhaustion, the amount of waste incident to the change 35 of the filling would be large and objectionable. On the other hand, should the feeler mechanism fail to call a change while there still remain sufficient filling in the shuttle to lay a full length of filling in the shed, 40 defective cloth is liable to be produced.

45 One of the objects of the present invention, therefore, is to provide a "side swipe" feeler mechanism wherein the feeler is given its side swipe or lateral movement longitudinally of the shuttle by forward pressure when the filling is substantially exhausted, and wherein, also, the parts are 50 simple in construction and sensitive both to

the presence and substantial absence of filling in the shuttle.

55

The present feeler mechanism embodies a feeler which is yieldingly held rearwardly in its feeling position and with permissive movement forwardly and in a direction longitudinally of the shuttle. Associated 60 and combined with the feeler is a deflector which, on a detecting beat, tends to effect side swipe or lateral movement of the feeler, and is prevented from accomplishing this 65 object by engagement of the feeler with the working supply of filling in the shuttle and to effect such movement when the filling is substantially exhausted.

The features of the present invention and the novel combination of parts will best be 70 understood from the following description and accompanying drawings of one good, practical form of the invention.

In the drawings:

75 Figure 1 is a perspective view of the feeler side of the loom, some of the parts being broken away for clearness of illustration;

Fig. 2 is an enlarged detached plan view showing the action of the feeler mechanism when a working supply of filling is present 80 in the shuttle on a detecting beat;

Fig. 3 is a view similar to that of Fig. 2, showing the relation of parts when the filling is substantially exhausted.

85 The loom frame 1 may be of usual or appropriate construction for supporting the operating parts. Secured thereto are the bearing brackets 2, one at each side of the loom for supporting the transverse or rock shaft 3 which is normally under the influence of a spring, not shown, for turning it counterclockwise into the position indicated in Fig. 1. The parts so far described are of usual construction, and further amplification is unnecessary.

95

Secured to and rising from the transverse or rock shaft 3 is the arm 4, to the upper end of which is pivotally connected at 5 the latch 6, the rear end of which, as at 7, is adapted to be engaged by an operating member 8 at times as will hereinafter appear, in order to effect replenishment of filling, as usual in this type of looms. The operating member 8 may be formed as part of or connected to the cam follower.

100

105 The loom frame has extended therefrom

the shipper stand 9, from which projects the slotted bracket 10. Mounted adjustably on the bracket 10 by means of the adjusting bolt 11, which passes through the slot 12 is 5 a bracket 13.

The bracket 13 supports the feeler stand, and in the present instance the feeler stand 14 comprises a plate having a front and rear upwardly bent end portion. The feeler 10 stand is adjustably connected to the bracket 13 by means of the bolts 15 which pass through a suitable slot 16 formed in the feeler stand, the construction being such that upon manipulation of the bolts or 15 grooves 15, the feeler stand may be adjusted toward and from the front of the loom.

The flange 17 extending upwardly from the feeler stand is provided with a slot 18 extending laterally thereof, and with an 20 opening 19, for the purposes as will presently appear.

The front flange or projection 20 which extends upwardly from the feeler stand is provided with the openings 21 and 22. 25 Mounted for reciprocating movement in the openings in the front and rear flanges or lugs is a feeler member 23, the rear end portion 24 of which is provided with teeth for engagement with a surface within the shuttle on a detecting beat. A spring normally holds the feeler 23 in its rearward position, and in the present instance the spring 25 is interposed between a shoulder 26 formed on the feeler and the front flange 20, the construction being such that the spring 25 normally effects movement of the feeler into its rearward position, but permits frontward movement thereof on a detecting beat. The feeler is provided with a stop to limit its 30 rearward movement, and in the present instance such stop is formed as a pin 26, Fig. 1, which engages the front flange 20 when the feeler is in its rearward position.

Mounted for reciprocating movement in 40 the front and rear flanges 20 and 17 respectively, and substantially in parallel relation with the feeler 23 is the deflector 27 which, on each detecting beat, exerts a yielding influence upon the feeler to move it in a direction longitudinally of the shuttle. In the present instance of the invention, the deflector 27 is provided with a shoulder 28 between which and the front flange 20 is a spring 29 normally acting to hold the deflector 27 in its rearward position. A stop 30 limits the rearward movement of the deflector 27 by engaging the front flange 20.

The rear end portion of the deflector 27 has an inclined surface which engages with 45 a part carried by the feeler as the latter is pushed frontwardly by a surface within the shuttle on each detecting beat, the tendency of such incline being to move the feeler longitudinally of the shuttle. In the present 55 illustrated form of the invention, the rear

end portion of the deflector is turned laterally at 31, and has the rearwardly and laterally inclined surfaces 32 and 33. The portion 31 of the deflector, in the present instance, passes through an opening 34 in the 70 feeler, the construction being such that should the feeler 23 be pushed frontwardly, it would engage the rear inclined surface 32 of the deflector and have imparted to it a tendency to move laterally. Likewise, on 75 the rearward movement of the feeler, when it has been previously moved laterally or to the left, Fig. 1, the incline 33 acts to restore the feeler to its initial feeling position.

In order that the lateral movements of the 80 feeler may be properly limited, the end portion 31 of the deflector is provided with a stop 35 at one side of the feeler member and a stop 36 at the other side thereof, the construction being such that the lateral or 85 side movement of the feeler will be limited by the stops 35 and 36.

The lay, as usual, carries the shuttle box 37, the front wall of which is slotted at 38 to register with a corresponding slot 39 in 90 the front wall of the shuttle 40 when the latter is properly boxed. The shuttle 40 carries the usual filling carrier or bobbin 41 on which the filling 42 is wound.

The slot 34 in the feeler acts as a guide 95 which provides a front and a rear surface or wall for engagement with the incline surfaces of the deflector upon relative movement of the feeler member and deflector. In the present instance, the guide or slot 34 100 has its rear wall preferably inclined, as best indicated at 43, Figs. 2 and 3, and its front wall similarly inclined, as indicated at 44, the construction being such that should the feeler 23 be moved frontwardly, the leading 105 edge of the wall 43 in the feeler will travel frontwardly in contact with the inclined surfaces 32 of the deflector, and if the filling is absent or substantially absent from the shuttle, the effect of the incline 32 will be to move 110 the feeler laterally as it moves frontwardly. Similarly, when the feeler moves rearwardly after a detecting beat, the leading edge of the wall 44 will ride along the inclined surface 33 of the deflector after the latter comes 115 to rest in its rearward position, and effect lateral movement of the feeler toward its true feeling position as indicated in Figs. 1 and 2.

The present invention utilizes this side or 120 lateral movement of the feeler for effecting replenishment of filling, and in the present instance the feeler has connected thereto at 46 a link or rod 45, the other end of which is connected at 47 to a bell crank lever 48 pivotally mounted at 49 on a stand 50 rising from the loom frame. One arm 51 of the bell crank lever underlies the latch 6, the construction being such that upon movement 125 of the feeler member 23 laterally to the left, 130

Fig. 1, the bell crank will be turned upon its pivot and place the end 7 of the latch in the path of movement of the operating member 8, and cause replenishment of filling. 5 A stop 52 may be provided for limiting the movement of the bell crank 48 in one direction as indicated in Fig. 1.

When a working supply of filling is present in a shuttle on a detecting beat, the 10 toothed end 24 of the feeler will engage and sink into the filling as the lay moves frontwardly, and will hold the feeler 23 from lateral movement due to the pressure between the guide 34 and the incline surface of 15 the deflector, as the two move frontwardly. When, however, the filling is substantially exhausted on a detecting beat, as indicated in Fig. 3, the filling will no longer be able to hold the feeler from lateral movement due 20 to the frontward pressure against it as the lay beats up, and the leading edge of the wall 43 of the feeler will ride along the incline surface 32 of the deflector, due to the frontward pressure against the feeler, and effect 25 lateral movement of the feeler. This lateral movement will be transmitted through the connection 45 of the bell crank 48 and cause replenishment of filling when the operating 8 moves frontwardly.

30 Since the feeler member not only moves frontwardly, but has also a lateral movement, the guide bearing 21 in the front flange 20 is made rounded and of sufficient size to permit such lateral movement of the 35 feeler, as indicated in Figs. 2 and 3.

What is claimed is:

1. In a feeler mechanism for looms, the combination of a feeler and a deflector each mounted for movement toward and from 40 the front of the loom, one of said members having an inclined surface which is engaged by the other member and tends to move the feeler laterally under the frontward pressure against the feeler on a detecting beat to effect replenishment of filling and is prevented from effecting such lateral movement by engagement of the feeler with the filling until substantial exhaustion thereof, and means connected to the feeler 45 for effecting replenishment of filling.

2. In a feeler mechanism for looms, the combination of a feeler which is mounted for movement toward the front of the loom on each detecting beat regardless of the 55 amount of filling in the shuttle, a deflector, means for independently supporting the deflector and feeler, interengaging inclined parts between the feeler and deflector which tend to effect movement of the feeler longitudinally along the filling carrier on each 60 detecting beat and which are prevented from effecting such movement of the feeler by engagement of the feeler with the filling on each detecting beat until substantial exhaustion of the filling.

3. In a feeler mechanism for looms, the combination of a feeler mounted for frontward and lateral movements, a deflector mounted for frontward movement and having a laterally inclined portion which crosses 70 the feeler when the latter is in normal position, and a part carried by the feeler which bears upon said inclined portion of the deflector as the feeler is pushed frontwardly on a detecting beat and which tends to impart lateral movement to the feeler and effect such lateral movement when the filling is substantially exhausted on a detecting beat.

4. In a feeler mechanism for looms, the combination of a feeler stand, a feeler 80 mounted for longitudinal and lateral movements on the stand and having a lateral guideway, a deflector mounted for longitudinal movement on the feeler stand and having a laterally-extending inclined portion 85 that passes through the lateral guideway of the feeler, and means for effecting replenishment of filling when the feeler is moved laterally due to the frontward pressure upon it and the inclined portion of the 90 deflector.

5. In a feeler mechanism for looms, the combination of a feeler stand, a feeler mounted on the stand, and having a lateral 95 opening, and a deflector having a laterally inclined end portion extending through the lateral opening of the feeler and acting to effect lateral movement of the feeler by the frontward pressure of the feeler against said inclined end portion when the filling is substantially exhausted on a detecting beat.

6. In a feeler mechanism for looms, the combination of a feeler stand, a feeler mounted on the stand and having a lateral 105 opening, a deflector having a laterally inclined end portion extending through the lateral opening of the feeler and acting to effect lateral movement of the feeler by the frontward pressure of the feeler against said inclined end portion when the filling is substantially exhausted on a detecting beat, and a stop on the deflector for limiting the lateral movement of the feeler, and means for effecting replenishment of filling 110 when the feeler is moved laterally.

7. In a feeler mechanism for looms, the combination of a feeler stand, a feeler mounted on the stand and having a lateral opening, a deflector having a laterally inclined end portion extending through the lateral opening of the feeler and acting to effect lateral movement of the feeler by the frontward pressure of the feeler against said inclined end portion when the filling is substantially exhausted on a detecting beat, 120 and a stop on the deflector at each side of the feeler for limiting its lateral movements.

8. In a feeler mechanism for looms, the combination of a feeler having a laterally extending guideway, and a deflector having 125

a laterally extending inclined portion passing through said guideway for moving the feeler laterally in one direction as the feeler is moved forwardly and for moving it laterally in the opposite direction as the feeler moves rearwardly, and means actuated by lateral movement of the feeler in one direction for effecting replenishment of filling.

9. In a feeler mechanism for looms, the combination of a feeler stand, a feeler mounted on the stand, a deflector mounted on the stand substantially parallel to the feeler and having a rearwardly inclined end portion which passes through the feeler in a direction inclined to its longitudinal axis, and means for effecting replenishment of filling when the feeler is moved laterally by the inclined end portion of the deflector on a detecting beat.

10. In a feeler mechanism for looms, the combination of a feeler which is mounted for movement toward and from the front of the loom on each detecting beat regardless of the amount of filling on the filling carrier in the shuttle, a deflector, interengaging cam portions on the feeler and deflector which, under the forward pressure on a detecting beat, tend to cause the feeler

to move along the filling carrier to effect replenishment of filling, but are prevented from effecting such movement until the filling is substantially exhausted, and means for effecting replenishment of filling when the deflector succeeds in moving the feeler along the filling carrier.

11. In a feeler mechanism for looms, the combination of a feeler which is mounted for movement toward and from the front of the loom on each detecting beat regardless of the amount of filling on the filling carrier in the shuttle, a deflector, interengaging cam portions on the feeler and deflector which, under the forward pressure on a detecting beat, tend to cause the feeler to move along the filling carrier to effect replenishment of filling, but are prevented from effecting such movement until the filling is substantially exhausted, stops for limiting the amplitude of movement effected by the cam portions, and means for effecting replenishment of filling when the deflector succeeds in moving the feeler along the filling carrier.

In testimony wherof I have signed my name to this specification.

ISAAC SNOW.
